UNITED STATES PATENT OFFICE.

HARRY C. HOWER, OF CHICAGO, ILLINOIS.

DESIGN FOR AN AUTOMOBILE TIRE.

Application filed October 22, 1928. Serial No. 28,591. Term of patent 7 years.

To all whom it may concern:

Be it known that I, HARRY C. HOWER, a citizen of the United States, residing at Chicago, in the county of Cook and State of Illinois, have invented a new, original, and ornamental Design for Automobile Tires, of which the following is a specification, reference being had to the accompanying drawing, forming a part thereof.

In the drawing,

Fig. 1 is a plan view of a portion of a tire embodying the present design;

Fig. 2 is a fragmentary side elevational view of the tire shown in Fig. 1; and
Fig. 3 is a transverse radial section taken on the line 3—3 of Fig. 1.

I claim:

The ornamental design for an automobile tire, as shown.

In witness whereof, I hereunto subscribe my name this 19th day of October, 1928.

HARRY C. HOWER.
